US00D902177S

(12) **United States Design Patent** (10) Patent No.: **US D902,177 S**
(45) Date of Patent: **** Nov. 17, 2020**

(54) **WIRELESS SPEAKER**

(71) Applicant: **SHENZHEN GRANDSUN ELECTRONIC CO., LTD.**,
Guangdong (CN)

(72) Inventors: **Huakun Zhang**, Shenzhen (CN);
Haiquan Wu, Guangdong (CN); **Weili Chen**, Shenzhen (CN); **Ruiwen Shi**, Shenzhen (CN)

(73) Assignee: **SHENZHEN GRANDSUN ELECTRONIC CO., LTD.**, Shenzhen (CN)

(**) Term: **15 Years**

(21) Appl. No.: **29/697,485**

(22) Filed: **Jul. 9, 2019**

(30) **Foreign Application Priority Data**

Jan. 9, 2019 (CN) 2019 3 0010770

(51) LOC (12) Cl. **14-01**

(52) U.S. Cl.

USPC **D14/206**; D14/226

(58) **Field of Classification Search**

Dickinson Wright PLLC

(57) **CLAIM**

The ornamental design for a “wireless speaker”, as shown and described.

DESCRIPTION

FIG. 1 is a perspective view of a wireless speaker;
FIG. 2 is a front view thereof;

FIG. 3 is a rear view thereof;

FIG. 4 is a left side view thereof; a part is shown separately
for ease of illustration;

FIG. 5 is a right side view thereof; a part is shown separately
for ease of illustration;

FIG. 6 is a top view thereof; and,

FIG. 7 is a bottom view thereof.

The broken lines in the figures depict portions of the wireless
speaker that form no part of the claimed design.

1 Claim, 7 Drawing Sheets
